(57) **CLAIM**

The ornamental design for a construction member, as shown and described.

DESCRIPTION

FIG. 1 is a front, right perspective view of an embodiment of my design, the front left side perspective view is a mirror image;

FIG. 2 is a front elevation view of the embodiment of FIG. 1, the rear elevation view is the same;

FIG. 3 is a right side view of the embodiment of FIG. 1, the left side view is a mirror image;

FIG. 4 is a top plan view of construction member of FIG. 1, the bottom plan view is the same;

FIG. 5 is a front, right perspective view of an alternate embodiment of my design, the front left side perspective view is a mirror image;

FIG. 6 is a front elevation view of the alternate embodiment of FIG. 5, the rear elevation view is the same;

FIG. 7 is a right side view of the alternate embodiment of FIG. 5, the left side view is a mirror image; and,

FIG. 8 is a top plan view of the alternate embodiment of FIG. 5, and the bottom plan view is the same.

The construction member has been broken to indicate indeterminate length.
